(57) **CLAIM**

The ornamental design for a telescopic feather duster rod, as shown and described.

DESCRIPTION

FIG. 1 is a front perspective view of a telescopic feather duster rod, showing my new design;

FIG. 2 is a left side perspective view thereof;

FIG. 3 is a front elevational view thereof;

FIG. 4 is a left side elevational view thereof;

FIG. 5 is a top plan view thereof;

FIG. 6 is a bottom plan view thereof;

FIG. 7 is an enlarged view of portion 7 in FIG. 1;

FIG. 8 is an enlarged view of portion 8 in FIG. 5; and,

FIG. 9 is an enlarged view of portion 9 in FIG. 6.

In FIGS. 1-2, 5 and 8, dash-dot-dash broken lines inside the cone shape of the telescopic feather duster rod depicts a boundary that forms no part of the claimed design. The other dash-dot-dash broken lines in FIGS. 1 and 5-9 depict enlargement indications that form no part of the claimed design. The dash-dot broken lines in FIGS. 5 and 8 depict portions of the telescopic feather duster rod that form no part of the claimed design.
